UNITED STATES PATENT OFFICE.

JOHN EDWARD WRIGHT, OF PITTSBURGH, PENNSYLVANIA, ASSIGNOR TO WRIGHT
TELEGRAPHIC TYPEWRITER COMPANY, OF NEW YORK, N. Y., A CORPORATION OF
DELAWARE.

TRANSLATOR FOR PRINTING-TELEGRAPH SYSTEMS.

1,090,367.

Specification of Letters Patent. Patented Mar. 17, 1914.

Application filed January 22, 1913. Serial No. 743,511.

To all whom it may concern:

Be it known that I, JOHN E. WRIGHT, a citizen of the United States, residing at Pittsburgh, county of Allegheny, and State of Pennsylvania, have invented certain new and useful Improvements in Translators for Printing-Telegraph Systems, of which the following is a full, clear, and exact description.

10 In an application filed by me on December 9, 1912, Serial No. 735,682, I have shown a printing telegraph receiver in which the selection and printing of characters, spacing, paper feed and such other functions as 15 are involved in the operation of a column printing telegraph instrument, are effected by means of electromagnetic devices, each having its special function and connected up with one of a plurality of circuits local to 20 the instrument, in such manner that each particular operation, or series of certain operations, results from the completion of a corresponding circuit or the simultaneous completion of two or more circuits. In the 25 case of an instrument constructed on this principle, it is manifest that special provision must be made for the control of the numerous local or receiver circuits by the minimum number of line circuits, and my 30 present application is concerned with, and based upon, an instrument which may be called a translator, and which is employed as an element in a system of the kind described, intermediate to the receiver and the 35 line circuit and which operates in response to current impulses of definite character transmitted over the line to complete the appropriate and corresponding circuits in the receiver.

40 The invention upon which this application is based resides in improvements in the construction of the translator and in certain combinations incident thereto, and for purposes of a more ready understanding 45 thereof, reference will be made to the drawings accompanying and forming a part of this specification.

Figure 1 is a front view in elevation of my improved translator. Fig. 2 is a top plan view of the same. Fig. 3 is a similar view, but with the upper portions of the parts removed to exhibit the mechanism beneath. Fig. 4 is a sectional elevation on line x-x of Fig. 1 looking toward the left. Fig.

5 is a similar view on lines y-y. Fig. 6 is 55 a view in elevation of a detail of mechanism. Fig. 7 is a view in elevation and part section of the instrument on line z-z but omitting the parts shown in Fig. 6. Fig. 8 60 is a diagram of circuit connections.

The instrument is mounted on a base plate 1, having two rigid side plates 2 and 3, across which extends in front, an angle bar 4, and in the rear, a bar or plate 5. A bar 6 which also extends along the base plate in front contains a series of equi-distant slots or saw cuts in which the ends of a series of levers 7 are pivoted, the upper ends of said levers extending through slots in the angle bar 4, as shown in Fig. 4. To each of 70 said levers 7 a spiral spring 8, secured at its opposite end to a cross bar 9, is connected and operates to hold said lever in engagement with a cross bar 10 normally defining the limit of forward movement of the 75 levers.

Extending across the device and sliding in suitable openings in the side plates 2 and 3, is a group of five flat bars 11, 12, 13, 14 and 15 which have the following special 80 conformation: At its right hand end each bar has a projection 16 slotted at its ends to receive a steel wire spring 17 secured to the base plate 1, that tends to hold the bar in proper alignment and force it toward the 85 left. Each bar along that portion which projects beyond the side plate 2, contains a long notch, and at regular intervals in said notches studs 19 are placed in position to normally engage pivoted levers 18 and prevent the oscillation thereof. The left hand ends of the said bars, which project beyond the side plate 3, with the exception of the middle bar 13, are bent or spread as shown in Fig. 1, to engage with a corresponding 95 series of levers 30, the nature and purpose of which will be described later. Finally, each bar along its forward edge contains a series of notches which occupy different positions in the respective bars, so that in 100 the normal position of the group none of the levers 7 may be shifted through their full operative arcs, but when any one or more or all of the bars are shifted to the right a predetermined distance, the notches 105 of all the bars in the group will coincide at one point and permit the correspondingly placed lever 7 to be drawn forward to its full

extent. In other words, the bars constitute a series of permutation racks or bars, which, according to their relative adjustment, permit one of the levers 7 to be shifted into operative position.

The bars are moved or adjusted for this purpose by the co-operative action of five selecting magnets 22, 23, 24, 25 and 26; a shifting or releasing magnet 27 and the intermediate mechanism illustrated in Figs. 1, 2 and 5. The selecting magnets are arranged in any convenient manner so that the armature lever of each may engage one of a series of five pins 28, sliding in a rigidly supported block 29. These pins are so located as to engage corresponding pivoted levers 30, mounted in a frame which is adapted to slide in guides formed in the supporting plate or frame 31 for the selecting magnets.

The levers 30 are normally held out of engagement with the permutation bars by means of light spiral springs 32, but when any of the selecting magnets is energized and its corresponding pin 28 forced forward, the lever 30, which is engaged thereby, is turned to bring its end into the path of its corresponding permutation bar, and retained in such position by one of a series of spring-actuated latches 33, Fig. 3, pivoted to the magnet supporting plate 31.

The magnet 27, preferably in the form of a solenoid, is provided with armature cores 34 carried by a reciprocating rod 35 mounted in suitable fixed bearings and equipped with a retractile spring 36. The said rod 35 is pivotally connected to an arm 37 rigid with a vertical rock shaft 38, an arm 39 from which is connected with and operates to oscillate the frame carrying levers 30.

Mounted on the base of the instrument in the rear of the parts described is a solenoid or magnet 40, the armature of which is spring seated by means of a rod 41 and a spiral spring 42. The armature yoke 97 is pivotally connected with a bell-crank lever 43, itself pivoted to a stud secured to the plate or bar 5, and through such connection to the bar 10, by means of the connecting rod 44. The bar 10 is supported on a rock shaft 45 by arms 20, and is held in its normal or forward position by an arm or latch 46 extending from a rock shaft 47 and actuated by a spiral spring 48. The bar 10 is forced to this position, if not already in it, by the operation of magnet 40, and released and permitted to swing back through a limited arc by a device shown in Figs. 3 and 7. This latter consists of a bell-crank lever 49 pivoted to the plate 2. One arm of the said lever is connected with a sliding rod 98, having a connection, with provision for lost motion, with the armature of magnet 27, and by the reciprocation of said rod is oscillated, bringing its other end into engagement with

and lifting an arm 50 rigid with rock shaft 47. This movement of the lever 49 disengages the latch or arm 46 from the bar 10 and permits the latter to swing backward through a short arc.

With the exception of such details of mechanism as are incidental to the main operation and which will be more readily understood in connection with the description of such operation, the above described parts constitute, in the main, that element of the system which may be considered as the translator proper. I have already explained that the function of this device is to control the various circuits local to the receiver or printing mechanism, and it will be understood that the specific means by which the several elements of the instrument itself are operated to effect this result are in a large measure immaterial. As the device is constructed, however, it requires that current impulses be introduced to it through eight different paths, seven of which may be designated as line controlled circuits and which are as follows, viz., the five including the selecting magnets, one including the magnet 27, and the last a special magnet 51 which has to do with a certain operation of the printing mechanism and will be more fully hereinafter described, and one which is a receiver controlled circuit and includes the magnet 40. In practice the current impulses, with the exception of those for energizing the clearing magnet 40, are derived from such a device as a sunflower disk at the transmitting station or one at the receiving end of the line operating synchronously therewith, either with or without the usual relays as occasion may require.

In an application filed by me on January 22nd, 1913, Serial Number 743,512, such a transmitter is shown and described as one of the elements of the system with which the instrument of this application is designed to be used, and the apparatus referred to is not, for this reason illustrated herein. In so far, however, as the construction and mode of operation of the instrument of my present application are concerned, the sunflower mentioned may be entirely disregarded and eight independent line wires assumed which deliver current impulses in the proper order to those circuits in the translator above referred to as the "controlled" circuits. For the more ready identification of the circuits in the instrument and their relation to corresponding circuits in the receiving and transmitting instruments respectively, the contact plates of Fig. 2 which are intended to be connected with the receiver terminals, are designated by the letters *a* to *n*, and those which are to be connected to line, or which constitute terminals of the controlled circuits, by the letters *p* to *v*. The contact

plates in Fig. 2 counting from the left, correspond with the leads 52 to 76 inclusive of Fig. 8, there being, however, one additional plate which may be disregarded.

5 With this understanding the operation of the instrument will be readily understood by reference to Fig. 8.

10 The terminals of the instrument, as above stated, are designated by the numerals 52 to 76 inclusive, and the proper connections are to be established between these and the terminals of the instruments controlling and controlled by the device.

15 The five selecting magnets are included in independent circuits from terminals 52 to 56 inclusive, to terminal 74, which is grounded. Assume, then, that an impulse of current coming in at terminal 52 energizes selecting magnet 22. The armature of this magnet forces inward its corresponding pin 28, and, 20 engaging the lowermost of the series of levers 30, shifts its end into the path of the bottom bar 15, in which position it is held by its latch 33. Following this action, an impulse of current coming in at terminal 58, from the line instruments, energizes 25 magnet 27 which effects the following series of operations: The bell crank lever 49 is tilted, the arm 50 raised and the arm 46 which holds the bar 10 in its forward or normal position is withdrawn, permitting that 30 bar to swing backward, as hereinbefore described. The rock shaft 38 is also turned with the result of shifting to the right the frame carrying levers 30, but as only the 35 lowest lever is in the path of a permutation bar, the corresponding bar, in this case that marked 15, alone will be shifted to the right.

40 Each one of the series of levers 18, as above stated, is normally confronted by one of a series of studs on the respective permutation bars. The stud 19 on bar 15, lies in the path of that lever 18, which is the first 45 in the group, counting from right to left. By the movement of said bar, therefore, above described, this stud will be shifted to the right of the path of said lever and the latter thus permitted to swing forward into 50 the notches in the pile of bars. As soon, however, as this forward movement occurs, the stud engages with the right hand side of the lever, and retains the bar 15 in its shifted position, after the return of the 55 levers 30 to their normal position on the interruption of the current impulse in magnet 27.

By the aforesaid movement of the bar 15 the notches in the five bars opposite the first 60 or left hand lever 7, are brought into alignment, and that lever alone of the entire series is permitted to complete its full swing into the opening thus provided.

All of the levers 7 are connected together 65 electrically by the frame of the machine and

are grounded through the wires 79, 80 and 81, and the contact spring 82 on the armature of a magnet 83, the specific purpose of which will be described later. Facing each lever 7 is a movable contact 78 and a stationary contact 77. In the commercial instrument each stationary contact is mounted on a special plate, as shown in Fig. 2, and from these the proper connections are made by insulated wires. The plan of connections is illustrated in Fig. 8, in which 84, 84^a, 84^b, and 84^c represent metal plates insulated from the frame of the machine and connected, respectively, to terminals 64, 65, 66 and 67. The first four stationary contacts 77, counting from the left on each plate, are insulated from the plates but connected by insulated wires with special terminals, as shown in the diagram, as will be hereinafter explained. The fifth stationary contact on each plate is connected directly with the plate.

The movable terminals are adapted to be forced into contact with the plates by the movement of the lever 7. Plate 84^d has no 90 connection with any terminal.

Having assumed above that the first lever 7, on the left, is permitted to swing on its pivot and thereby bring its two appropriate contacts 77 and 78 into engagement, it will 95 be understood from the foregoing that the movable contact 78 is thereby connected through plate 84 with terminal 64, which controls that local circuit in the printer which, when energized, lifts the type-wheel 100 through one line space. The stationary terminal 77, which is insulated from the frame of the machine, is connected with terminal 60 which controls that local circuit in the printer which, when active, turns the type-wheel 105 through one step or two character spaces. By the forward movement, therefore, of the first lever 7, which carries its confronting movable contact 78 into engagement with the stationary contact 77, two circuits, viz., from terminals 60 and 64 to ground will be rendered active, and, under the conditions assumed, that character will be printed which for its presentation to the printing position requires the type-wheel to 110 be turned one step, or through an arc including two character spaces, and lifted one step, or through one line space.

The operations of the printer attendant upon and following the selection and printing of each character sends a current impulse back to the translator through the terminal 59 which includes in its circuit to the ground terminal 74, the magnet 40. This latter, when energized, depresses one end of 115 a lever 99 pivoted beneath the base plate 1, as shown in Fig. 7, the other end of which lever raises a rod 79 engaging with a frame 80 composed of right angle or bell-crank side levers with bars connecting their free 120 125 130 135 140 145 150 155 160 165 170 175 180 185 190 195 200 205 210 215 220 225 230 235 240 245 250 255 260 265 270 275 ends. The upper bar of the frame is thus brought in contact with the levers 18 and forces out of engagement with bar 15 the right hand lever. This releases the bar 15, which, by the action of the spring 17, engaging therewith, is forced back to its normal position.

Another operation effected by the magnet 40 is that of forcing forward the bar 10 through the instrumentality of the rod 44, whereupon it is engaged by the latch 46 and held in its forward position. Thus, the function of magnet 40, which following every operation of the receiving or printing instrument brought about by the action of the translator, is energized by a receiver controlled circuit, clears the translator and leaves it in condition to respond to the next transmitted impulse or series of impulses.

Assume now, by way of illustration, that a series of impulses compose the signal received by the translator, for example, that an impulse is sent into each circuit from terminals 52, 53 and 54. This energizes magnets 22, 23 and 24, and three bars 13, 14 and 15 will be shifted by the action of magnet 27. This results in a permutation of the notches in said bars that permits the ninth lever 7, counting from the right, to move forward. In this case the stationary contact 77 is grounded through its corresponding movable contact 78 and the lever 7, but as the movable contact has no connection with any other circuit, but acts merely as a bridge between the stationary contact 77 and the lever 7, but one circuit, that to terminal 60, will be completed. This controls the receiver circuit that imparts a turning movement of one step or two character spaces to the type wheel.

In further illustration, assume that a given signal sends impulses into the circuits from terminals 54 and 55, thus energizing magnets 24, 25. The result of this will be to force the two permutation bars 12 and 13 forward, which permits the twelfth lever 7, counting from the right, to operate. This lever, because its movable contact is electrically connected with the adjacent plate 84°, closes two circuits, one to terminal 62 through the fixed stop 77, which imparts a turning movement of three steps or six character spaces to the type-wheel of the receiver, the other to terminal 67 through plate 84° that lifts it four steps.

It will thus be seen that any of the receiver controlling circuits 60 to 73 inclusive, may be completed by shifting one or more of the permutation bars and permitting the levers 7 to close either one or two circuits, as the case may be, the selection of bars to be shifted depending upon the selecting magnet or magnets energized.

In the drawings of the apparatus there is shown in Figs. 3 and 6, an electro-magnet

51, with a spring actuated armature 87, having an extension 88, adapted when depressed to engage with a shoulder on one arm of a spring actuated bell-crank lever 89 pivoted at 89°. By reference to the diagram Fig. 8 it will be seen that magnet 51 is in a circuit leading from terminal 57. This magnet is termed the shift-magnet, and its function is to close the circuit to terminal 73, which is extended to that circuit of the receiver which shifts the type-wheel through one character space, independently of the mechanism that turns it through one, two, three or four steps, each of which includes two character spaces. When a character is to be printed, therefore, which is in the first or any other odd numbered vertical line on the type-wheel, a current impulse is sent into the circuit of this magnet either alone or in addition to impulses sent through any one or more of the selecting magnets whereby the type-wheel will be lifted or turned through one or more steps and shifted through one character space in addition, to bring the desired character to the printing position.

The operation of the clearing magnet 40, which, as previously described, raises the rod 79, Fig. 7, lifts the latch arm of the bell-crank lever 89, and releases the armature of magnet 51 whenever the latter has been operated. The combination of this shift magnet with the system of permutation bars herein described, results in a very great simplification of the instrument by practically doubling its capacity. For example, by closing the circuit of the magnet 51 the additional function of shifting the type-wheel in the receiver through one character space is added to the functions of each lever 7.

It will be observed that the operation of magnet 27 precedes, since it causes, the movement of the levers 7, which operate to close one or more circuits by bringing together contacts 77 and 78. From the nature of the levers and contacts a certain amount of vibration necessarily accompanies their operation, and this would ordinarily result in objectionable sparking. This I prevent by the use of a circuit controller which, when the magnet 27 is energized, will be operated and caused to break the ground connection of all of the levers 7. As the operation of the magnet is almost instantaneous, this ground connection will be broken for a correspondingly short time, but the interruption of the same is sufficient to include the interval of harmful vibration of the levers 7 and the contacts operated thereby. It will also be understood that on the operation of the clearing magnet 40, which restores the levers 7 to normal position, the breaking of the circuit completed by the lever which has been called

into operation would be attended by an objectionable spark, but this also may be prevented by grounding the circuit from levers 7 through a condenser bridging a break in said circuit.

In practice the devices for effecting these two operations are conveniently combined in a single electrically controlled mechanism as shown in Fig. 8. The magnet 83 in that diagram is shown as provided with a spring retracted armature composed of a pivoted bar 95 and a contact spring 82. Normally, the bar 95 maintains the spring 82 in engagement with a contact that completes the circuit from wire 79, leading from levers 7 to wires 80 and 81, running to the grounded terminal 74, and a condenser 96^a is connected up by wire 96 to terminal 75 which bridges the contacts.

Instead of using a single electrically controlled device for the above described operations, mechanical circuit controllers for accomplishing the same purpose may be used if so desired. For example, a controller for interrupting the circuit at any point between the levers 7 and the terminal 74 may be such a device as shown in Figs. 2 and 3, and which is composed of a pivoted spring actuated contact lever 90 and a plunger rod 91 in the path of the arm 37, so that when the magnet 27 is energized, the contact arm 90 will be operated. As the operation of the magnet is almost instantaneous, the return of its armature allows the contact lever 90 to immediately return to normal position. So also for interrupting the ground circuit and bridging the break through a condenser on the operation of the closing magnet 40 there may be combined with the armature yoke 97 of said magnet the circuit breaker shown in Fig. 4. This consists of an insulated spring plunger 92 which is normally in contact with a terminal 94 on an insulated arm 93 on the armature yoke. If the path from levers 7 to ground be across the two members 92 and 94, the instant that the armature is moved by the magnet, such circuit will be interrupted.

It will be understood that while I have described the invention as part of a printing telegraph system, by which term is specifically intended a system comprising a receiving instrument adapted to print characters corresponding to the signals transmitted, it is applicable to similar systems for the transmission of intelligence, for example, those in which the signals are made visible by the use of a receiver which displays letters, numbers or words, and are usually designated as indicators.

What I claim is:

1. In a translator for printing telegraph systems, the combination with a series of receiver controlling circuits and a series of

line controlled circuits, of a plurality of circuit controllers, certain of which are adapted when operated to complete single receiver circuits, and others a plurality of such circuits simultaneously, and electromagnetically operated selecting devices connected with the line controlled circuits for bringing into operation the said circuit controllers corresponding to definite signals transmitted over the line.

2. In a translator for printing telegraph systems, the combination with a series of receiver controlling circuits and a series of line controlled circuits, of movable contact controlling levers, certain of which, when operated, complete single receiver circuits and others two of such circuits simultaneously, means connected with a line controlled circuit for operating said contact levers, and selecting magnets connected with line controlled circuits for determining the contact lever so operated, according to the signal transmitted to the translator.

3. In a translator for printing telegraph systems, the combination with a series of receiver controlling circuits, and a series of line controlled circuits, of a series of movable contact controlling levers, certain of which when operated complete single receiver circuits and others two of such circuits simultaneously, a set of sliding permutation bars normally restraining all of said contact controlling levers from operation, an electro-magnet on a line controlled circuit for shifting the bars and selecting magnets included in line controlled circuits for determining the particular bar or bars to be shifted to permit the operation of the contact levers corresponding to the signals transmitted to the translator.

4. In a translator for printing telegraph systems, the combination with a series of receiver controlling circuits and a series of line controlled circuits, of circuit controllers in the receiver circuits, selecting devices in the line controlled circuits for operating the circuit controllers according to the signals transmitted over the line, an electro-magnet in one of the line controlled circuits, and a circuit controller in one of the receiver controlling circuits adapted to be operated by the action of said magnet.

5. In a translator for printing telegraph systems, the combination with a series of receiver controlling circuits and a series of line controlled circuits, of circuit controllers in the receiver circuits, selecting devices in the line circuits for bringing the same into operation according to the character of the signals transmitted, a circuit breaker common to all of the receiver circuits and means controlled by a line circuit for operating the same to interrupt the receiver circuit for intervals during which the circuit controllers are making contact.

6. In a translator for printing telegraph systems, the combination with a series of receiver controlling circuits and a series of line controlled circuits, of circuit controllers in the receiver circuits, selecting devices in the line circuits for bringing into operation the circuit controllers according to the character of the transmitted signals, a circuit breaker common to all of the receiver circuits, an electromagnet in a receiver controlled circuit for operating the same at the instant of the separation of the circuit controller contacts, and a condenser circuit in shunt to said circuit breaker.
15. 7. In a translator for printing telegraph systems, the combination with a series of receiver controlling circuits, and a series of line controlled circuits, selecting devices in the line controlled circuits, circuit controllers in the receiver circuits operated thereby according to the character of the signals transmitted, a special shift-magnet receiver controlling circuit, and an electro-magnetic circuit controller therein included in a line controlled circuit actuated independently of the operation of the selecting devices.
8. In a translator for printing telegraph systems, the combination with a series of receiver controlling circuits and oscillating contact levers for controlling the same, of a series of notched permutation bars co-operating with said contact levers, means for shifting one or more or all of said bars to bring notches into alignment at different points, a series of line controlled circuits, electromagnets therein and means operated thereby for selecting the bar or bars to be shifted.
9. In a translator for printing telegraph systems, the combination with a series of receiver controlling and a series of line controlled circuits, of circuit controllers in the receiver circuits, means operated by the line circuits to select for operation the circuit controllers corresponding to predetermined signals transmitted over the line, a circuit breaker in a circuit common to all of said circuit controllers, a magnet adapted to be energized by a line controlled and also by a receiver controlled circuit for operating said circuit breaker, and a condenser bridging the contacts of the circuit breaker.
10. In a translator for printing telegraphs, the combination with line controlled selective magnets, of stops actuated thereby, means for locking the actuated stops in operative position, a line controlled magnet, receiver controlling mechanism selectively operated by said magnet according to the number and position of the actuated stops, and means for releasing the locked stops, operated by the energizing of said magnet.
11. In a translator for printing telegraphs, the combination with line controlled selective magnets, of stops actuated thereby, means for locking the actuated stops in operative position, a line controlled magnet, receiver controlling mechanism selectively operated by said magnet according to the number and position of the actuated stops, means for locking said mechanism when brought to operative position, means for releasing the locked stops dependent for operation on that of said magnet, and means for releasing the receiver controlling mechanism dependent for operation on that of the receiver.
12. The combination of a series of line controlled magnets, stops as 30 adapted to be actuated thereby, latches 33 for locking said stops in the position to which they may have been shifted by their respective magnets, a series of movable permutation plates, a line controlled magnet 27 for shifting said plates according to the number and position of the actuated stops, and means controlled by said magnet for releasing the locked stops in the operation of shifting the permutation plates.
13. The combination of a series of line controlled magnets, stops as 30 adapted to be actuated thereby, latches 33 for locking said stops in the position in which they may have been shifted by their respective magnets, a series of permutation plates corresponding in number and position to said stops, a line controlled magnet 27 for operating said plates by a movement of the series of stops, whereby the plates corresponding to the selectively actuated stops will be shifted, and means for releasing the locked stops by such movement.
14. The combination of a series of line controlled magnets, stops as 30 actuated thereby, latches for locking said stops in the position to which they may have been shifted by their respective magnets, a series of movable permutation plates, a line controlled magnet 27 for setting the plates in positions determined by the selective stops that may have been actuated, means for locking the plates when brought to operative position, means for releasing the stops dependent for operation on that of the magnet 27, and means for releasing the plates dependent for operation on that of the receiver.
